SEWING-MACHINE.

1,253,614.

Specification of Letters Patent. Patented Jan. 15, 1918.

Application filed March 16, 1914. Serial No. 824,873.

To all whom it may concern:

Be it known that we, ROBERT L. LYONS, of Waltham, in the county of Middlesex, HAROLD W. MORRIS, of Roxbury, in the county of Suffolk; and CARL I. NIELSEN, of Arlington, in said county of Middlesex, all in the State of Massachusetts, have invented certain new and useful Improvements in Sewing-Machines, of which the following 10 is a specification, reference being had to the accompanying drawings, forming part thereof.

This invention has reference to improvements in sewing machines and particularly 15 to such machines as are adapted to attach by sewing stitches tags or other flat devices to a fabric.

The object of the invention is to so construct a sewing machine, particularly a single thread sewing machine, that a tag or other flat article may be attached to a fabric by a group of stitches, that the relative movement of the work with respect to the stitch forming devices may be arrested during the sewing of one or more tying stitches 25 and that the sewing thread may be strained to break said thread.

Other objects of the invention are to facilitate the operation of the various parts 30 of the machine as, for instance, the release and return of the lifter plate to its normal position.

The invention consists in the novel means for lifting the work to strain the thread.

35 The invention also consists in such other novel features of construction and combinations of parts as shall hereinafter be more fully described and pointed out in the claims.

Figure 1, represents a side elevation of 40 parts of a sewing machine to illustrate our new invention.

Fig. 2, represents a sectional plan view of portions of the same as taken on line 2—2 Fig. 1.

45 Fig. 3, represents a vertical sectional view of some of the parts as taken on line 3—3 Fig. 1 to show the means for raising the cloth lifter plate or member and for automatically releasing said plate to permit said 50 plate to return to normal position before the presser foot descends.

Fig. 4, represents a detail view of the presser foot in combination with the lifter plate.

Fig. 5, represents, approximately, one 55 product of this improved machine; the fabric *a* having the tag *b* attached to said fabric by the sewing stitches *c*, *c*.

Fig. 6, represents a detail view of the cam for holding the thread clamp actuating 60 rod from release movement.

Similar characters of reference designate corresponding parts throughout.

We are aware that buttons have been attached to fabric by groups of stitches and 65 that, after the formation of tying stitches, said button and its attached fabric has been lifted to strain and break the thread. In such operation the button has such stability that it is engaged by the arms of a button 70 clamp and the lifting of the work to effect the breaking of the thread is accomplished by the swinging upward of the arms of the button clamp. In carrying our present invention into practice the tag or flat article 75 which is to be attached to the fabric has neither the shape nor the stability to be engaged by a lifting device adapted to apply sufficient strain to effect the breaking of the sewing thread. The tag referred to 80 herein is often of paper or of comparatively thin cloth and is therefore not adapted to resist any severe strain. We therefore find that it is desirable and often necessary to effect the straining of the thread by lifting the under fabric by means of a cloth plate against which said under fabric rests during the sewing operation. This preferred means of lifting the work to strain 85 the thread usually requires the return of the cloth plate to normal position, to receive the work, before the presser foot is returned to its normal position to bear on the work.

In order to more fully describe the new improvement reference is now made to the 95 drawing in which 10 represents the bed plate of a sewing machine having the standard 11 furnished with the arm 12 having the head 13 by which head 13 operatively sustains the needle bar 14 which, with its 100 needle, cooperates with the usual looper mechanism 15 located beneath the plate 10.

The means for operating the needle mechanism and the looper mechanism may be of any known construction and does not necessarily form part of the present invention.

5 The frame arm 12 has the thread tensions 16 and 17, the posts 18 and 19 and the thread guide 20, post 18 having the pivoted arm 21 which may coöperate with post 19 to clamp a thread or to frictionally engage 10 a thread therebetween. Said pivoted arm 21 is operated in one direction by a spring and in the other direction by the slide rod 22 which is slidable in the guide 12' and has the pin members 23 and 24. The lower end 15 of said slide rod 22 is in position to be acted upon by the rise 25 of cam 26 which latter is adapted to be rotated by the driving mechanism of the machine, in any known manner, and has a cam or path 27 20 of any known shape to effect the vibration of the follower 28, engaged with said cam, during a period in the rotation of said cam 26 and to arrest such vibration during another period in the rotation of said cam 26 25 as is well known.

On the base plate 10 is movably mounted a work holder having the post 29 and the forwardly extending member 30 which latter has the hinged cloth plate 31 extending forward to the path of the needle and having a slot which is in registry with slot 32 of presser member 33 which latter has spurs at its under side and is carried by arm 34 pivotally mounted on said post 29. Cloth plate 31 has also the guide 35 with which the forward end of the lifter arm 36 is slidably engaged, the rear end of this arm 36 being pivotally mounted on the post 37 which in turn is mounted on the bed plate 10.

40 In bearing members 38, 39 carried respectively by the arm 12 and head 13 is journaled the shaft 40 having the arm 41 which arm is adapted to be swung by the actuation of its connection 42 to effect the rocking of said 45 shaft 40 and the swinging of its thread puller arms 43 and 44 the former of which (43) is located back of the thread clamp (19, 21) to pull thread T through the tensions 16 and 17 when the thread is clamped 50 by said thread clamp to provide loose thread for the next sewing operation, after the thread has been released by said thread clamp. Thread puller arm 44 is free on said shaft 40 and has the finger 45 and the de- 55 pending member 46 which latter has the drawing spring 47, attached to arm 12, and tending constantly to draw this member 46 toward the machine arm 12 and to swing outward the upper end of said thread puller 60 arm 44 to take up slack thread between the thread clamp and the work. The outward swinging of said thread puller 44 under the action of spring 47 is limited by the stop 48 fixed on the machine arm 12 and coöoperating 65 with the finger 45 of puller 44 while the

movement of said thread puller 44 to the thread releasing position, against the action of spring 47 is effected by arm 49 fixed on said shaft 40 and engaged with said thread puller arm 44.

70 On shaft 40 is mounted the cam 50 which, when shaft 40 is partially rotated, engages pin 23 of rod 22 and effects the partial rotation of said rod 22 until pin 23 rides on to the peripheral portion of said cam 50 as 75 shown in Fig. 6 and is sustained thereby to hold the thread clamp member 21 in the closed position. In starting a new sewing operation the primary movement of the work holder causes the rear end of its member 34 to strike pin 24 of said rod 22 whereby said rod is partially rotated and its pin 23 is released from the periphery of said cam 50 and is permitted, by the shape of said cam, to move downward thus releasing 80 thread clamp member 21 from the closing action of rod 22 and permitting the spring of said member 21 to act to open the thread clamp.

85 Mounted on shaft 40 is the arm 51 with 90 which is pivotally connected the lifter rod 52 having the cam 53 and, at or near its lower end, the engaging member 54. This lifter rod 52 is drawn toward the machine arm 12 by the spring 55 and said arm 12 is 95 provided with the cam 56 which in the upward movement of rod 52 acts against cam 53 of said rod and forces said rod to swing outward whereby the member 54 thereof is caused to move outward, from the position 100 shown in Fig. 2, sufficiently to release the lifter arm 36 whereby said arm 36 and its cloth plate 31 may fall back to position on the bed plate irrespective of the position of the presser arm 34 which latter is raised by 105 its connection 57 with the arm 58 of shaft 40.

110 With parts in position shown in Fig. 1 it is necessary to raise the presser foot 33 in order to introduce the cloth or fabric a and the tag b between said presser foot and 115 the cloth plate 31. This is preferably accomplished by manually actuating the connection 42 of arm 41 whereby shaft 40 is partially rotated and arm 58 is swung to draw up said presser foot 33 by means of the connection 57. At the same time the block or member 54 engages and draws up the lifter arm 36 and the cloth plate 31 is thus raised until the cam 53 of rod 52 rides against cam 56 and is, by said cam 56, 120 forced outward sufficiently to disengage member 54 from the lifter arm 36 thus permitting said arm 36 and plate 31 to drop back to a position where plate 31 is spaced from presser foot 33.

125 The material a with its tag b is now inserted between plate 31 and presser foot 33 and the connection 42 is released to permit the retractive rotation of shaft 40 and the downward movement of the presser foot 33 130

whereby the material *a* and tag *b* are engaged by the spurs on said presser foot and cloth plate as is indicated in Fig. 4.

With the material *a* and tag *b* in position, as just above described, the machine is operated and a group of stitches is sewn through *a* and *b* and at or about the completion of said group of stitches the relative movement between the work and the needle is arrested, by cam 26, in the usual manner and one or more tying stitches is formed. The automatic stopping of the machine is timed with relation to the formation of said tying stitch or stitches and, preceding said stopping, the rise 25 of said cam 26 acts on the slide rod 22 to raise said rod and to thereby move thread clamp member 21 against the action of its spring to the closed position whereby thread *T* is clamped or engaged between members 21 and 19 so that the forward movement of the thread is resisted.

Connection 42 is now actuated or effected to rock or partially rotate shaft 40 and as a result of said partial rotation several operations occur, the sequence of which occurrence depends somewhat upon the relative positions and dimensions of the members carried by or actuated by the rotative movement of said shaft 40. Cam 50 acts on pin 23 of rod 22 and effects the swinging of said pin on to the periphery of said cam 50 whereby said rod 22 is held in position to resist the opening movement of thread clamp member 21. Thread puller arm 43 is swung to draw thread through the tensions 16 and 17 or through one of said tensions if one only be used. Thread puller arm actuator 49 is moved or swung outward to permit spring 47 to swing thread puller arm 44 to take up slack thread between the thread clamp (19, 21) and the tying stitch at the work. Arm 58 is swung to draw upward presser foot arm 34 by means of the connection 57. Arm 51 is swung to draw up rod 52 which acts, through its member 54 on the lifter arm 36 to effect the lifting of the cloth plate 31 whereby the work is lifted and a strain is put upon the thread *T* to break said thread, the break occurring at the tying stitch.

Before the upward movement of rod 52 is completed its cam 53 rides against cam 56 and cam 53 and its rod 52 is caused to swing outward whereby the member 54 of said rod 52 is disengaged from lifter rod 36 and said rod and its cloth plate 31 are caused to move downward under gravity or by the assistance of the spring of said rod 36. By thus returning cloth plate 31 to normal position said plate 31 is spaced from presser foot 33 so that work may readily be placed between these parts.

When connection 42 is permitted to move upward shaft 40 is retractively rocked

whereby thread puller arm 43 is swung backward out of the way of the thread. Actuator arm 49 acts to effect the backward swinging of thread puller arm 44. Arm 58 in its movement permits the downward movement of presser foot arm 34, and arm 51 permits rod 52 to move downward until its member 54 rides against lifter arm 36 and thus become engaged beneath said arm 36 as indicated in Fig. 3, this engaging movement, laterally, of rod 52 and its member resulting from the action of spring 55.

When the machine is again started the rear portion of presser foot arm 34, in making its first vibratory movement, strikes pin 24 of rod 22 and causes said pin to swing whereby rod 22 is partially rotated to bring its pin 23 into the position shown in Fig. 1 where said pin 23 may be received in the groove of cam 50 to permit the downward movement of said rod 22 and the opening movement of thread clamp member 21 under action of its spring.

It is not our intention hereby to limit our invention to the specific features of construction herein shown or to the relative operation of some of the parts but only as herein claimed.

Having thus described our invention we claim as new and desire to secure by Letters Patent:

1. A sewing machine comprising stitch forming means to form a group of stitches and a tying stitch and including a work holder for effecting relative movement between the work and the needle, said work holder having a presser foot and a cloth sustaining plate, means adapted to be operated to resist the movement of the thread, and means for operating said cloth plate to move the work and thus to break the thread.

2. A sewing machine comprising stitch forming means and a work holder coöperating to form a group of stitches and a tying stitch, said work holder having a cloth sustaining member mounted on said work holder and movable relative to such holder, means for moving said member, and means for resisting the feeding movement of the thread at times to break the thread.

3. A sewing machine comprising stitch forming means and a work holder coöperating to form a group of stitches and a tying stitch, said work holder having a member engaged beneath the work for moving the work, means for operating said member to lift the work, a thread clamp, means for taking up the slack thread between said clamp and the stitch forming means, and means for operating said thread clamp and take up whereby thread may be broken.

4. A sewing machine comprising a work holder having a presser foot and a cloth sustaining member mounted for independent movement, means for moving said presser

foot and retaining the same, means for moving the cloth sustaining member relative to said presser foot and for releasing said member whereby said member may return to 5 normal position.

5. A sewing machine comprising a work holder having a presser foot and a cloth sustaining member both pivotally mounted, mechanism for moving both said presser foot 10 and sustaining member in one direction approximately simultaneously and for permitting the return of the sustaining member to its normal position independently of the presser foot.

15. 6. A sewing machine comprising coöperating means for forming a group of stitches and a tying stitch and including a member movable independently of the presser foot in a direction to draw the thread, means lo-

cated above the stitch forming devices for 20 resisting the movement of the thread, and means for moving said member to strain and break the thread.

7. A sewing machine comprising a work holder having a presser foot and a work 25 carrying member both pivotally mounted for relative upward movement, a lifter rod pivotally mounted on a member independent of said work holder and releasably engaged with said work carrying member, means for 30 moving upward said lifter rod, and means for moving upward said presser foot.
